SKI-CLIMBER

Filed Dec. 1, 1942

August H. Sage.

UNITED STATES PATENT OFFICE

2,375,943

SKI-CLIMBER

August H. Pape, Kentfield, Calif., assignor of one-half to Edward Kendal, San Francisco, Calif.

Application December 1, 1942, Serial No. 467,543

6 Claims. (Cl. 280—11.13)

My invention relates to skis and more particularly pertains to an attachment therefor known as ski-climbers, by means of which a skier may easily climb slopes or hills with a "straight-ahead" walking action.

An object of my invention is to provide ski-climbers which are securely locked on the skis in out-of-the-way position when not in use, and subject to a quick and easy shifting into climbing position in which they are locked and held on the skis, the shifting of the climbers from climbing position into and the locking thereof in out-of-the-way position being as readily and easily effected.

Another object of my invention is to provide a ski-climber of the character described in which a climbing blade and a ski-carried locking means are especially constructed and arranged to facilitate the mounting and locking of the blade in the out-of-the-way or the climbing position with one hand while the skis are strapped on the skier.

A further object is to provide a ski-climber of the character described in which the climbing blade is of exceptionally light yet strong construction and designed to embrace and be locked against opposite sides of the skis in both the out-of-the-way and climbing positions, with the blade securely braced against movement in any direction when in climbing position and held in such manner that it is not likely to become bent, twisted or deranged.

A further object of my invention is to provide a locking means for securely holding the blade in out-of-the-way and climbing positions and which may be locked and unlocked with one hand while the ski is strapped on the foot and when unlocked will so remain whereby the shifting of the blade from out-of-the-way to climbing position and vice versa may be easily effected and the locking of the blade then carried out with a single movement.

Another object of my invention is to provide a ski-climber which is designed so that collections of snow and ice will not interfere with the operation thereof and accumulations of snow and ice on the blade may be readily and easily dislodged.

With the foregoing objects in view, together with such other objects and advantages as may subsequently appear the invention resides in the parts and in the combination, construction and arrangement of parts hereinafter described and claimed, and illustrated by way of example in the accompanying drawing, in which:

Fig. 1 is a fragmentary side elevation of a ski equipped with a climber embodying my invention, with the blade in climbing position;

Fig. 2 is a sectional view on the line 2—2 of Fig. 1;

Fig. 3 is a side elevation of the climber when the blade is mounted in out-of-the-way position;

Fig. 4 is an enlarged fragmentary side elevation showing a detail of the climber when the blade is mounted in out-of-the-way position;

Fig. 5 is a cross sectional view on the line 5—5 of Fig. 3;

Fig. 6 is a top plan view of the climber when the blade is in out-of-the-way position;

Fig. 7 is a fragmentary part top plan, part sectional view of the climber when the lock is released with the blade in position shown in Fig. 6;

Fig. 8 is a fragmentary top plan view showing the blade locked in climbing position;

Fig. 9 is a side elevation of a complete ski showing the blade in climbing position thereon and the relation thereof to the foot.

Fig. 10 is a fragmentary side elevation of the ski as shown in Fig. 9 with the blade in out-of-the-way position.

Referring to the drawing more specifically, 1 designates a substantially rectangular climbing blade which is somewhat curved at its ends and adapted to be mounted on a ski 2 in two positions, one of which as shown in Figs. 3 and 10 being the out-of-the-way position on top of the ski, and the other the climbing position in which the blade depends from and extends transversely across the underside of the ski as shown in Figs. 1, 2, and 9.

Plate-like flanges or arms 3 are provided at the ends of the blade 1 and extend beyond one longitudinal edge of the blade so that in the out-of-the-way position said arms will overlie the side edges of the ski substantially parallel to said edges, whereas in the climbing position of the blade said arms will extend over said side edges at right angles to their former position and perpendicular to the ski. In this manner the arms 3 embrace the side edges of the ski in both positions of the blade to provide, as will be herein-after apparent, for a secure holding and locking of the blade in said two positions.

Brackets 4 and 5 are mounted on the upper side of the ski and each generally includes a horizontal portion 6 lying upon the upper side of the ski, and an upright ear portion 7 adapted to lie against a side edge of the ski to project up-

wardly above the ski. Openings 8 for locking bolts 9 are provided in the upper ends of the ear portions 7. Ears 10 are struck upwardly at the inner ends of the horizontal portions 6. A holding plate 11 having T-shaped slots 12 in opposite ends is secured by means of screws 13 to the upper side of the ski with the ears 10 engaged in said T-slots to secure the brackets on the ski. Other screws 14 are inserted through the ear portions 7 of the brackets into the sides of the ski to hold the brackets in place together with the holding plate 11.

The bolts 9 are slideable in and between the ears 7 and 10, said bolts having reduced inner ends 15 defining shoulders 16 to engage the ears 10 for limiting the inward or releasing movement of the bolts to position in which the outer ends thereof extend somewhat into the openings 8 as shown in Fig. 7. Stop pins 16' on the bolts limit the outward movement thereof.

The outer ends of the arms 3 are reduced to define tongues 3' having openings 17 therein adapted to register with the openings 8 in the ears 7, so that the locking bolts 9 may be extended to lock the tongues 3' to the bracket as shown in Figs. 5, 6, and 8, when the blade is in either of its two positions.

Cooperating stop means on the brackets 4 and 5 and arms 3 provide for limiting the movement of the arms to position in which the openings 8 and 17 register when mounting the blade in the out-of-the-way as well as the climbing position. These means also provide for an effectively braced mounting and holding of the blade in its two positions particularly so as to evenly distribute the strain and stresses set up when the blade is in use, whereby all likelihood of twisting or bending, or derangement of the blade and the locking means is eliminated. As here provided the stop means include shoulders 18 on opposite sides of the tongues 3', which shoulders are adapted to engage slotted flanges 19 formed on and projecting outwardly from the lower edges of the ears 7. The tongues 3' are extended through the slots 20 in the flanges 19 when the blade is mounted in climbing position and the shoulders 18 will abut lower sides of the flanges 19 as shown in Fig. 1. These shoulders and flanges limit the tongues to position in which the openings 17 therein register with the openings 8 in the ears 7. These stop shoulders also limit the blade to position in which the upper edge thereof is spaced from the lower side of the ski as shown in Figs. 1 and 2 whereby the skiing surface of the ski will not be damaged. The strain is solely taken up by the shoulders 18 and flanges 19 which thus insures a secure bracing and holding of the blade in climbing position.

Abutment plates 21 are secured by means of the screws 14 to the ears 7 at opposite ends of the slotted flanges 19 and rest on said flanges. The side edges of the tongues 3' engage the plates 21 to give added support and further reinforce the blade and supporting brackets therefor.

When the blade is in out-of-the-way position as shown in Figs. 3, 4 and 5, notches 22 in certain of the shoulders 18 receive tongues 23 formed on plates 24 which lie between certain of the abutment plates 21 as shown in Fig. 4. This locks the arm 3 on the sides of the ski with the openings 17 therein in registry with the openings 8 in the ear portions 7 of the brackets whereby the locking bolts 9 may be extended to lock the blade in out-of-the-way position. The tongues 3' in this position of the blade lie between the ears 7

and the plates 21 associated with the plates 24 as seen in Figs. 3 and 4.

As a means for operating the locking bolts 9, an inverted U-shaped spring 25 has its ends inserted through the bolts 9 so that the spring will urge the bolts into locking position. An operating plate 26 has openings 27 in its ends slidably receiving the legs of the U-shaped spring. When the plate 26 is pushed inwardly it forces the ends of the spring toward one another and thereby retracts the bolts, this retraction movement being limited by the shoulders 16 engaging the inner ears 10 as seen in Fig. 7. The plate 26 will remain by friction in position to which it is moved on the spring 25.

When the tongues 3' are in position to register the openings 17 therein with the openings 8 in the brackets 4 and 5, the operator may pull the plate 26 outwardly, thereby releasing the spring 25 so that the bolts will be forced by the spring into the registering openings 8 and 17 to thereby lock the blade in place, this operation being the same when the blade is in its out-of-the-way and climbing position respectively.

A block 28 of wood or other suitable material is mounted on the ski as a rest for the blade when in out-of-the-way position. This block also acts as a centering means to facilitate the mounting of the blade in out-of-the-way position and is provided with a notch 29 to receive the operating plate 26 as shown in Fig. 1.

On the portions 7 are inwardly struck spurs 30 as shown in Figs. 2 and 5 which bite into the side edges of the ski and assist in holding the brackets 4 and 5 in place.

It should be noted that the blade, that is, the arms 3 are flared as shown in Fig. 2 so that snow packed in the blade may be readily and easily removed.

With reference to Figs. 1, 9 and 10, it is seen that the climber of my invention may be conveniently mounted just rearward of the foot rest 31 on the ski so that the skier may have ready access thereto. However, it could be mounted forwardly of the foot rest if desired and in either case may be quickly and easily placed and locked in position of use or in out-of-the-way position with one hand while the ski is held on the foot.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, bracket means mounted on the ski, said bracket means and arms having openings therein adapted to register with one another when the blade is in climbing and out-of-the-way positions, stop members on the bracket means disposed on the sides of the ski, stop shoulders on said arms adapted to engage said stop members for limiting the movement of said arms relative to said bracket means to positions bringing said openings into registration with one another when the blade is being mounted in said out-of-the-way and climbing positions, locking

bolts slidable on the ski into and out of said openings for locking the blade in both positions thereof, and means for moving the bolts into and out of said openings to lock and release said blade.

2. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, bracket means fixed on the ski and overlying the sides of the ski, slotted flanges on said bracket means through the slots of which said arms extend when the blade is in climbing position, cooperating stop members on the flanges and said arms adapted to abut when the blade is in said two positions, and means for releasably locking said arms to said bracket means.

3. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, bracket means mounted on the ski, said bracket means and arms having openings therein adapted to register with one another when the blade is in climbing and out-of-the-way positions, cooperating stop members on the bracket means and said arms for limiting the movement of said arms relative to said bracket means to positions bringing said openings into registration with one another when the blade is being mounted in said out-of-the-way and climbing positions, locking bolts slidable on the ski into and out of said openings for locking the blade in both positions thereof, and means for moving the bolts into and out of said openings to lock and release said blade, including a spring having its ends attached to said bolts and normally urging said bolts into locking position, and an operating member slidable on said spring to contract and expand it for retracting and extending said bolts.

4. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, bracket means fixed on the ski and overlying the sides of the ski, slotted flanges on said bracket means through the slots of which said arms extend when the blade is in climbing position, stop shoulders on said arms for engaging said flanges when the blade is in said two

positions, cooperating holding elements on said bracket means and arms arranged to interlock when the blade is in said out-of-the-way position, and means for releasably locking said arms to said bracket means.

5. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, bracket means mounted on the ski, said bracket means and arms having openings therein adapted to register with one another when the blade is in climbing and out-of-the-way positions, cooperating stop members on the bracket means and said arms for limiting the movement of said arms relative to said bracket means to positions bringing said openings into registration with one another when the blade is being mounted in said out-of-the-way and climbing positions, locking bolts slidable on the ski into and out of said openings for locking the blade in both positions thereof, means for moving the bolts into and out of said openings to lock and release said blade, including a spring having its ends attached to said bolts and normally urging said bolts into locking position, an operating member slidable on said spring to contract and expand it for retracting and extending said bolts, and a block on the ski as a rest for the blade when in out-of-the-way position, said block having a notch therein to receive said operating member when the blade is locked in out-of-the-way position.

6. In a ski-climber, a climbing blade adapted to extend downwardly from and transversely across the underside of a ski when in climbing position and to lie upon the upperside of the ski in out-of-the-way position when not in use, arms on said blade adapted to overlie the side edges of the ski when in out-of-the-way and climbing positions, brackets mounted on said ski and having apertured upstanding ears thereon, portions of said bracket overlying the side edges of the ski, slotted flanges on said portions of the brackets adapted to receive the arms in the slots therein, shoulders on the arms adapted to engage said flanges when the arms are inserted through said slots, cooperating interlocking members on the arms and said brackets for holding the blade in out-of-the-way position, locking bolts slidably supported in said ears, said arms having openings therein to receive said bolts to lock the blade in out-of-the-way and climbing positions, and means for moving said bolts into and out of locking position.

AUGUST H. PAPE.
